COMBINATION GARMENT OR SO-CALLED
OVERALLSGerhard Herman Kayser, Lonneker, near
Enschede, NetherlandsApplication January 15, 1935, Serial No. 1,942
In the Netherlands September 14, 1934

2 Claims. (Cl. 2—79)

In the manufacture of garments comprising sleeves it has been proposed to provide such garment with means, which will allow the wearer free and unhampered movement of the arms and particularly raising the arms without unduly straining of the sleeves of the garment and consequent liability of tearing the sleeve from the armhole. To obtain this the edge of the sleeve opening is secured in the armhole along the upper portion only, whilst along the remaining portion it is provided with an extension piece or flap loosely overlapping the edge of the armhole at the inner side, such overlapping portion being connected to a lower point of the garment by an elastic band.

Such measure, which in the case of ordinary coats really would have no value, as in raising the arms the whole garment moves upwards, is however of special advantage for combined garments or overalls, in which the jacket and trousers are combined in a single unit, which is buttoned up to the neck and covers the undergarments completely.

It has been found that the application of the above-described measure per se does not produce the desired and expected result in overalls. It is true, that in raising the arms, a somewhat elastic displacement of the overlapping portion relative to the edge of the armhole takes place, but not to a sufficient extent, while in simultaneously turning the body forwards or backwards or when the arms are more laterally stretched, straining of the sleeves and consequent liability to tearing the sleeves from the armholes still occur. Also, the overlapping portion, when lowering the arms does not smoothly return to its original position, but produces folds at the side between the armhole and sleeve.

According to the invention a completely satisfactory solution of the problem is obtained, in that at either side of the overlapping portion there is provided in the breast and back of the garment an elastic pleat, to which the said overlapping portion is connected. Only by this combination of the above described known measure with the elastic pleats, a free and unhampered movement of the arms and body is allowed in all directions, without the risk of tearing the sleeves from the armholes and without inconveniently straining the garment.

The invention will be hereinafter described, reference being had to the accompanying drawing showing an embodiment of an over-all comprising the improvement according to the invention.

Fig. 1 shows the garment in front elevation and partly opened.

Fig. 2 is a back view of the garment.

As shown in the drawing, the back portion 1 of the jacket or upper part of the garment, along the total width of the back, is detached from the trousers 2 which, at this point, are provided with an approximately triangular flap 3 underlying said back portion 1, the apex of said flap being connected through the medium of an elastic band 4 to a higher point of the inner side of the back portion 1. The elastic band may be formed by a strip of elastic material having button-holes for engaging two buttons 5, 6 secured respectively to said flap and to the jacket. Preferably, the said strip has additional button-holes 7 for shortening the strip, when elongated.

For the fixing of the sleeves in the arm-pits the desired object is achieved in a corresponding manner.

The edge of the sleeve-opening is secured in the arm-hole along the upper part only, i. e. approximately down to the points 8. For the remaining lower part of said edge, the latter is detached from the edge 9 of the arm-hole, an approximately triangular flap 10 being provided on the sleeve to overlap the edge 9 of the arm-hole at the inner side, where it is connected from its apex to a lower point of the jacket through the medium of buttons 11, 12 and an adjustable elastic strip 13. Thus a relative elastic displacement is permitted, so that tearing of the sleeves in the arm-pits is prevented and the arms may be moved freely, the provision of the flap 10 in triangular form having the advantage of concentrating the pull of the strip 13 at a single point (the apex), whence it is distributed uniformly in the flap. Further, this form of flap enables the required functions to be performed by a single elastic strip 13, doing away with a necessity for more.

If desired, pleats 14, 15 may be provided on the bust and in the back portion of the jacket to obtain a certain slackness in the transverse direction. The expansion and contraction of the garment which these pleats afford in the region of the armpits provides such coordination with the sleeves as will let the flaps flatten out smoothly.

What I claim is:—

1. A garment comprising a body portion provided with armholes, a sleeve fitted to each armhole, the edge of the opening of the respective sleeve being secured in the armhole along the upper portion thereof, the remaining portion of the sleeve merging into a substantially triangular flap overlapping the edge of the armhole at the

inner side, an elastic band connecting the apex of the overlapping flap to a lower portion of the garment, and a pleat located on each side of the flap at the breast and back of the garment adjacent to said flap to provide for a predetermined slack in a transverse direction under the armpits of the garment to coordinate with the sleeve to let the flap flatten out smoothly.

2. A garment comprising a body portion provided with armholes, a sleeve fitted to each armhole, the edge of the opening of the respective

sleeve being secured in the armhole along the upper portion thereof, the remaining portion of the sleeve merging into a substantially triangular flap overlapping the edge of the armhole at the inner side, and an elastic band connecting the apex of the overlapping flap to a lower portion of the garment, the triangular form of said flap enabling a concentration of the pull of the strip to a single point whence it is distributed uniformly in the flap. 5
